UNITED STATES PATENT OFFICE.

CLAUDE W. STEWART, OF MARTINSBURG, WEST VIRGINIA.

VACUUM-SWEEPER.

1,324,416.

Specification of Letters Patent.

Patented Dec. 9, 1919.

Application filed March 13, 1919. Serial No. 282,263.

To all whom it may concern:

Be it known that I, CLAUDE W. STEWART, a citizen of the United States of America, and a resident of Martinsburg, county of 5 Berkeley, and State of West Virginia, have invented certain new and useful Improvements in Vacuum-Sweepers, of which the following is a full and clear specification.

This invention has relation to that type 10 of vacuum sweeper which employs a belt-driven rotary brush in the nozzle-chamber for the purpose of loosening the dirt in the floor-covering preparatory to its inspiration into the machine, and the object of the 15 present invention is to provide simple mechanism for stopping the motor when the rotary brush becomes clogged with ravelings wound upon it in sufficient quantity to stop the brush or impair its efficiency, as 20 more fully hereinafter set forth.

In the drawing—

The figure represents a side elevation of a well-known type of vacuum floor-sweeper partly in vertical section, showing my invention applied thereto.

In the drawing, *a* designates the usual brush which consists of a horizontal shaft provided with tufts of bristles and which is driven by a belt *b* from the usual pulley 30 *c* on the fan-motor-shaft. It frequently happens in this type of machine that strings, hair and ravelings wind upon the brush and accumulate thereon in sufficient quantity to cause sufficient binding against the 35 adjacent wall of the nozzle-chamber to entirely arrest the rotation of the brush. In this case, the machine, of course, becomes practically inoperative, and, if use of the machine continues while the brush is thus 40 clogged against rotation, the belt will slip on the small driven pulley *c* and result eventually in ruining the belt by burning. In view of the fact that a machine of this type will necessarily be used by persons of 45 little or no mechanical knowledge or experience, it frequently happens not only that the machine causes great dissatisfaction on the part of the user, but also that the belt will be destroyed before the trouble is under- 50 stood or discovered. My present invention is designed to provide simple means whereby the collecting on the brush of sufficient ravelings will automatically open the motor-circuit and thus stop the motor.

55 One way of applying my invention is to mount in the nozzle-chamber, just above and

to the rear of the brush, a finger or plate *d* curved to conform substantially to the general cylindrical shape of the brush and pivoted at its lower rear end on a horizontal 60 pivot *e* mounted in the rear wall of the nozzle-chamber, a hole being provided in said rear wall through which said rear end of the finger extends. This finger extends rearwardly beyond the pivot *e* and is connected pivotally at *g* to the lower end of an upright link *f* whose upper end is pivotally connected at *h* to the forwardly-extending arm *i* of a bell-crank, the upwardly-extending arm *j* of said bell-crank 70 being pivotally connected by a link *k* to a switch *l* which is the usual manually-operable motor-controlling switch of the machine.

In the drawing, the parts are shown in 75 the position they assume when the switch is on. In this position, the finger or plate *d* is close to the brush bristles and the switch-lever is pushed to the extremity in a rearward direction. Should ravelings accumulate on the brush, this accumulation will increase the diameter sufficiently to swing the plate or finger *d* upwardly and rearwardly, thus swinging the rear end of the finger downwardly. This downward movement of 85 the finger will pull link *f* downwardly and thus swing the vertical arm *j* of the bell-crank forwardly far enough to move the switch to off position, thus stopping the motor. In this simple way, all danger of 90 injury to the machine through the chocking of the rotary brush will be avoided, thereby rendering the machine virtually fool-proof. It will be understood that the tripping-finger or plate *d* may be duplicated or multiplied, so as to cover more or less of the area of the brush, and it will be understood further that the lever-and-link arrangement may be duplicated on the opposite side of the machine if it be found 95 desirable to do so.

The nature and scope of the invention having been thus indicated and its preferred embodiment having been specifically described, what is claimed as new is:

1. In a motor-driven vacuum sweeper employing a rotary brush in the nozzle-chamber and an electric switch for controlling the motor, a member adapted to be moved by the accumulation of ravelings on the brush, and means operated by said member for opening said switch.

2. In a motor-driven vacuum sweeper employing a rotary brush in the nozzle-chamber and an electric switch for controlling the motor, a member adapted to be moved by the accumulation of ravelings on the brush and curved to approximate the surface of the brush, and means operated by said member for opening said switch. 5
3. In a motor-driven vacuum sweeper employing a rotary brush in the nozzle-chamber and an electric switch for controlling the motor, a member adapted to be moved by the accumulation of ravelings on the brush, and means operated by said member for opening said switch, said means consisting of an arrangement of links and levers mounted upon the apparatus and connected to said member. 10
4. In a vacuum sweeper of the type set forth, a finger pivoted on the rear wall of the nozzle-chamber and having one end extending into the nozzle-chamber and lying adjacent to the cylindrical surface of the brush so as to be actuated by ravelings accumulated on the brush, the rear end of said finger being extended rearwardly through the wall of the nozzle-chamber, and means connected to said rearwardly-extending end to actuate the motor-switch. 15 20 25
5. In a vacuum sweeper in which the rotary brush is arranged in the nozzle and is driven by a belt connection with an electric motor controlled by an electric switch, a finger mounted in the nozzle-chamber at the upper rear side of the brush and adapted to be swung upwardly and rearwardly by ravelings accumulated on the brush, and means connecting said finger to said switch whereby actuation of the finger by said ravelings will throw the switch to off position. 30 35 40
6. In a vacuum sweeper in which a rotary brush is arranged in the nozzle and is driven from an electric motor controlled by an electric manually-operable switch, a member mounted in the nozzle-chamber and adapted to be actuated by ravelings accumulated on the brush, and positive means for connecting said member to said manually-operable switch whereby the manual manipulation of the switch to on position will automatically adjust the member to operative position, whereby the accumulation of ravelings on the brush will through said positive means shift the switch to off position. 45 50 55

In testimony whereof I hereunto affix my signature.

CLAUDE W. STEWART.
